(57) **CLAIM**

We claim the ornamental design for a cradle for a personal digital assistant, as shown and described.

DESCRIPTION

FIG. 1 is a front, top, left side perspective view of a cradle for a personal digital assistant showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a second perspective view of the cradle for a personal digital assistant shown in use.

The portions shown in broken line are for illustrative purposes only and form no part of the claimed design.
